CLAIM

The ornamental design for an upper torso robe as shown and described.

DESCRIPTION

FIG. 1 is a front view of a upper torso robe showing my new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof;

FIG. 7 is a front elevation view of a second embodiment of my new design thereof;

FIG. 8 is a right side elevation view of second embodiment of my new design thereof;

FIG. 9 is a left side elevation view of second embodiment of my new design thereof;

FIG. 10 is a top plan view of second embodiment of my new design thereof;

FIG. 11 is a bottom plan view of second embodiment of my new design thereof; and,

FIG. 12 is a rear elevation view of second embodiment of my new design thereof.

The broken lines in the figures depict portions of the Upper Torsos Robe that form no part of the claimed design.
